[57] CLAIM

The ornamental design for a testing tray, substantially as shown and described.

DESCRIPTION

FIG. 1 is a top plan view showing my new tray design, with the cover in the open position;

FIG. 2 is a front view of my tray;

FIG. 3 is a rear view of my tray in the condition of FIG. 1;

FIG. 4 is a side elevational view of my tray, in the open condition of FIG. 1; and

FIG. 5 is a top plan view similar to FIG. 1, with the cover closed.

FIG. 1

FIG. 2

FIG. 3

FIG. 4

FIG. 5
